UNITED STATES PATENT OFFICE

134,044

DESIGN FOR A COMBINED COSMETIC POWDER CONTAINER AND APPLICATOR

Albert E. Vaughn, Los Angeles, Calif.

Application November 14, 1941, Serial No. 104,154

Term of patent 14 years

To all whom it may concern:

Be it known that I, Albert E. Vaughn, a citizen of the United States, residing in Los Angeles, in the county of Los Angeles and State of California, have invented a new, original, and ornamental Design for a Combined Cosmetic Powder Container and Applicator, of which the following is a specification, reference being had to the accompanying drawing, forming part thereof.

Fig. 1 is a perspective view of a combined cosmetic powder container and applicator embodying my new design;

Fig. 2 is a side elevational view of the article in Fig. 1 with the top cover in raised position showing the applicator portion;

Fig. 3 is a top plan view thereof; and

Fig. 4 is a bottom plan view thereof.

I claim:

The ornamental design for a combined cosmetic powder container and applicator, as shown.

ALBERT E. VAUGHN.
